DESIGN FOR CARPET.

SPECIFICATION forming part of Design No. 24,224, dated April 16, 1895.

Application filed March 18, 1895. Serial No. 542,265. Term of patent 3½ years.

To all whom it may concern:

Be it known that I, ARTHUR MIDDLETON ROSE, residing at Yonkers, county of Westchester, State of New York, have invented and produced a new and original Design for a Pattern to be Wrought into Wilton and other Carpetings in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of a body A and a border B.

The body A is decorated with a geometric figure, or gem, appearing at regular intervals upon a shaded background.

The border B consists of a narrow band for

an inner edge, outside of which is shown the same geometric figure, or gem, as in the body, appearing at regular intervals, together with other geometric figures of similar style; also an outer edge or sub-border of ornamental figures.

What I claim as my invention, and desire to secure by Letters Patent, is—

1. In a design for a carpet, the body A, substantially as shown.
2. In a design for a carpet, the border B, substantially as shown.
3. The design for carpets, consisting of the body A, and the border B, substantially as shown.
